FEED MECHANISM FOR TYPEWRITERS

Thomas French, Rumford, Maine

Application March 21, 1935, Serial No. 12,172

16 Claims. (Cl. 197—130)

This invention relates to feed mechanism for a printing machine, and more particularly to mechanism for automatically feeding to and removing from typing position in a typewriter, or other printing machine, envelopes, post-cards or other similar material to be printed.

It is the object of this invention to provide mechanism which feeds material from a supply magazine, successively and without overlapping, to typing position on the impression cylinder provided in the usual typewriter; to allow a predetermined number of lines of printing to be affixed to the material thus fed; and to bring succeeding material to typing position on the impression cylinder and simultaneously to remove the printed material automatically from typing position and deposit it in a receiving device.

While the chief object of the device is to allow such automatic feed and removal, my invention is especially directed to mechanism which allows this continuous feed while at the same time not requiring more than one thickness of envelope to be held by the impression cylinder at any one time. Heretofore it has been suggested that the envelopes be fed around the impression cylinder in underlying relationship in order to have only the distance of one double space between the last line of typing on the preceding envelope and the position of the first line to be typed on the succeeding envelope, so that the latter will be brought to operating position by one double spacing after the former is completed. Two envelopes besides that being printed are therefore held by the impression cylinder after the typing operation has started. In the case of envelopes there is thus a thickness at places of six pieces of paper held by the impression roll. Such operation is described in 40 U. S. patent to H. L. Chenery, No. 1,817,235 of August 4, 1931.

My device provides mechanism which allows but one envelope to be engaged in the impression cylinder at any one point and by one simple movement of a lever the succeeding envelope is properly positioned for printing while at the same time the envelope just printed is removed. There is thus no overlapping or doubling up of the envelopes in the typewriter mechanism and the energy required to turn the impression cylinder is only that which is necessary in the usual typewriter operation.

The foregoing objects and advantages of my invention, together with others which will be set forth hereinafter, will be apparent from the fol-

lowing description taken in connection with the accompanying drawings in which:

Fig. 1 is a side elevation showing the essential portions of the usual typewriter with my feed mechanism affixed thereto; 5

Fig. 2 is a perspective view of the upper portion of my device with certain parts omitted;

Fig. 3 is a plan view of a typewriter with my device attached thereto;

Fig. 4 is a side elevation taken on the line 4—4 of Fig. 3 with the bottom portion broken away; 10

Fig. 5 is a front elevation taken on the line 5—5 of Fig. 3, also with parts broken away;

Fig. 6 is a rear elevation, partly broken away, taken on the line 6—6 of Fig. 3; 15

Fig. 7 is an enlarged elevation view taken from the right-hand side of the machine as from line 7—7 of Fig. 3;

Fig. 8 is in part a horizontal section taken on the line 8—8 of Fig. 7, and in part a plan; and 20

Fig. 9 is a cross-section taken on the line 9—9 of Fig. 8.

Referring to the drawings and particularly to Figs. 1 and 3, I have indicated generally a typewriter of the usual form, having a platen roll 2 mounted on the shaft 3 which in turn is supported on the reciprocating carriage 1 in the usual manner. The customary spacing lever 4 is provided which operates to revolve the platen roll 2, step by step a predetermined distance to space the lines vertically as is common in typewriting. The typewriter carriage 1 reciprocates from right to left as the typing proceeds and is moved in the opposite direction at the completion of a line of typing to return the carriage to starting position in the usual manner. 25

My mechanism involves broadly two co-operating feed mechanisms, one of which, indicated generally at A in Fig. 1, is devised to feed material, such as envelopes or the like, from a magazine, directly to certain feed rollers in the second feed mechanism which is indicated generally at B. The feed rollers of the second mechanism are adapted, in co-operation with the usual typewriter feed, to feed the material intermittently into operative position in front of the platen roll. The second feed mechanism also has additional rollers which reengage the material after it has been typed to deliver the material to a collecting device. 30

The second feed mechanism, which will first be described, is shown in detail in Figs. 7 and 8. Angle irons 5, shown in Fig. 8, are permanently affixed, one on each side of the typewriter carriage 1 in parallel relation as shown in Fig. 3. 35

Each of said angle irons 5 includes a side flange 5a rising vertically from its outer edge. The angle irons 5 with their side flanges 5a which are thus secured to the typewriter carriage 1 are 5 adapted to secure in proper position on the carriage the feed mechanism B which, after it has been assembled as a unit, is replaceably mounted between the side flanges 5a. The mechanism B is secured together as a unit prior to its insertion 10 between the side flanges 5a, by the plates 7, tied together and properly spaced from each other by the rod 9 suitably secured between the plates, and also by the shaft 11 mounted in bearings 10 in each of the plates 7. After assembly of the 15 B mechanism, constructed as hereinafter described, the mechanism and the plates 7 securing it together, are inserted between the flanges 5a and are removably secured thereto by any suitable means such as pins 6 fixed in the flanges 20 5a and co-operating with the slots 8 (Fig. 7) in the plates 7.

Fixed to the shaft 11 are the knurled feed rollers 12, gear 13 and pinion 14. Mounted to the 25 rear of the shaft 11 is the shaft 15 which carries, fixed thereon, the knurled feed rollers 20 whose peripheries are yieldingly urged toward the feed rollers 12 by means of the sliding bearings 16, in which the shaft 15 is journaled, spring-pressed in the direction of the shaft 11 by springs 18. Shaft 30 15 also carries fixed thereon the gear 19 meshing with gear 13 on the shaft 11. A third pair of knurled feed rollers 25 are mounted on the shaft 21 which, as indicated in Fig. 7, is disposed in front of the shaft 11 and above the same. The 35 shaft is held in bearing springs 22 which curve upwardly and forwardly from the bearings 10. The springs 22 function to urge yieldingly the peripheries of feed rollers 25 toward the feed rollers 12. Shaft 21 is driven from shaft 11 by means of 40 the gear 24 fixed on the former shaft and engaging gear 13 fixed on the latter. The teeth on gears 24, 13, and 19 are sufficiently long to permit the relative yielding movement between the feed rollers without disengagement of the 45 gears.

The feed rollers 25, 12, and 20 are rotated at the proper time for the purpose of feeding material, as hereinafter described, by a rotation imparted to the pinion 14 on the shaft 11, through 50 the following train of mechanism. Pinion 14 meshes with gear 28 rotatably mounted on a sleeve 109 which in turn is mounted on the stud shaft 27 projecting from arm 26 which, for the purpose of certain adjustments hereinafter to be 55 described, is pivoted on the outside of the bearing 10 by means of a split sleeve which can be secured in any desired position radially of the shaft 11 by means of the screw 26a. The gear 28 is in turn driven by pinion 29 (Fig. 7) which, as indicated in Fig. 1, is fixed on the shaft 3 on which (Fig. 3) the platen roll is mounted. The purpose of mounting gear 28 on stud shaft 27, which can be secured in various positions radially of the shaft 11, is to position gear 28 for proper mesh 60 with pinion 29 on the end of shaft 3 upon assembly of the B unit between angle irons 5. The gear train 29, 28, 14, 13 and gears 24 and 19 are so constructed and the diameters of the feed rollers 25, 12 and 20 proportioned relative to the 65 diameter of platen roll 2 that the said feed rollers and the platen roll travel at the same peripheral speed.

As indicated in Fig. 1, the shafts 3, 21, 11, and 15 are so positioned relative to each other, that 70 the feed rollers 12 and 20 carried by the shafts

11 and 15 are adapted to feed material delivered to the feed rollers 12 and 20, downwardly to the rear of the platen roll 2 carried by shaft 3 and between it and the idle feed rollers behind the platen roll 2 which are commonly provided on 5 typewriters.

As indicated in Fig. 3, guide fingers 95 project over the top of the platen roll and engage the leading edge of the material, as it emerges upwardly over the front surface of the platen roll 10 and direct it upwardly and rearwardly between feed rollers 25 and 12.

Further details of the mechanism for rotating feed rollers 12 and 20 will be hereinafter described.

The feed mechanism designated generally at 15 A in Fig. 1 is adapted to deliver material from a storage receptacle to the said feed rollers 12 and 20. The mechanism A is supported above and to the rear of the main typewriter mechanism by the frame 30 which is suitably secured to the 20 frame proper of the typewriter in any suitable manner as by angle irons 31 which are secured to the frame 30 and engage any suitable cross bar on the bottom of the frame of the typewriter, and by brackets 32 affixed to each side of the 25 frame 30 and receiving screws 34 having at their forward end lugs 33 which engage the fixed upright members at the rear sides of the typewriter.

The frame 30 supports a platform 35, provided with suitable sides 36 to form a box-like container adapted to receive and store the envelopes and other material 37 (Fig. 2). For the purpose of accommodating envelopes of different lengths the sides 36 are preferably constructed for adjustment laterally of the typewriter proper and to 30 that end I mount each side 36 on the platform 35 for sliding movement laterally of the frame 30 and I further provide each side 36 with an arm 123 (Fig. 3) which extends toward the center of the machine and terminates in a rack 120 engaging a 35 pinion 121 manually rotated by a thumb piece 122 (Fig. 1). Obviously rotation of the thumb piece 122 is effective to adjust each of the sides 36 an equal amount away from or toward the center of the machine. 45

The envelopes 37 are constantly urged forwardly against a stop element 38 (Fig. 2) on the forward part of the frame, by a movable pusher element 39 which is adapted for movement longitudinally of the container and is guided in its 50 movement by suitable slots 40 (Fig. 3) in the platform 35 receiving and co-operating with suitable tongues or other co-operating elements projecting from the bottom of the pusher 39. The pusher 39 is constantly urged forwardly by a cord 55 43 attached at 43a to the bottom of pusher element 39 and extending therefrom around the idle roller 44 to the drum 41 which contains a spring or other suitable mechanism which urges clockwise rotation of the drum 41 as viewed in 60 Fig. 1.

As indicated in Fig. 2 a stack of envelopes 37 to be typed are inserted in the container with the flaps of the envelopes at the bottom and facing the front part of the machine. The pusher 39, 65 as stated above, urges the stack of envelopes forwardly and against the stop 38. The mechanism now to be described is adapted to engage the flaps of individual envelopes and feed them downwardly to the above-described feed rollers 12 and 20. 70

To ensure that the envelopes which are pressed forwardly against the stop 38 do not of their own accord slip over the leading edge 35a of the platform 35, I provide a pair of extensions 126 flush with the supporting surface of the platform 35 75

and by these extensions 126 I ensure that no envelopes are removed from the stack 37 except those which are mechanically engaged and fed by the feeding elements now to be described.

5 The envelope engaging elements of the feed mechanism comprises the fingers 51 which, as indicated in Fig. 2, engage behind the flap of the leading envelope. For the purpose of providing the necessary vertical feeding motion of the feed fingers 51, I mount the said fingers on the cross bar 50, the opposite ends of which are mounted at the extremities of levers 46. For the purpose of moving the bottom edge of the leading envelope out over the extensions 126 I provide 10 that the fingers 51 are not only reciprocable vertically, but are also adapted to rotate slightly in a counter-clockwise direction as viewed in Fig. 2 and to that end the bar 50 to which the feed fingers 51 are rigidly secured is mounted in bearings 50a in the extremities of the arms 46.

15 The normal position of the feed fingers 51 is backwardly against the leading envelope of the stack and a yielding pressure of the fingers in that direction is obtained by means of the torsion spring 52 encircling the bar 50 and secured at one end to the said bar and at the other end to the arm 46.

20 The vertical reciprocation of the feed fingers 51 is produced automatically by the reciprocation of the carriage 1 carrying the platen roll 2, through the mechanism now to be described. The arms 46 on which the bar 50 is pivotally mounted are themselves pivoted at 47 (Fig. 1) to the frame 30 and are provided with suitable 25 spring elements 48 which urge the arms 46 in clockwise rotation from the full line position of Fig. 1 to the dotted line position. Pivoted at 79 to the arms 46 are the links 78. Pivoted at 77 to the links 78 are the arms 76 which are in turn fixed to a shaft 75 which, as indicated in 30 Fig. 6, extends crosswise of the machine and is suitably journaled in the side walls of the frame. Rotation of the shaft 75 is effected by the crank arm 74 secured to the shaft 75 and connecting the link 72 by the universal joint 73. The opposite end of link 72 is connected by means of universal joint 71 to one arm 70 of a bell crank lever pivoted at 69, the other arm 68 of which projects upwardly and is adapted to engage and be actuated by certain adjustable stop mechanism attached to the reciprocating carriage 1.

35 The carriage 1 has fixed thereto and adapted to reciprocate therewith a fixed projection 63 and disposed adjacent the path of reciprocation of the projection 63 is the slide 60 mounted on a rod 61 fixed at both ends in the frame 30 and extending parallel to the direction of reciprocation of the carriage and projection 63. Said slide 60 is provided with lug 62 extending into the path of movement of the slide 60 and the 40 lug 62 is constantly urged toward the stop 64 on the rod 61 by the spring 65 attached to the slide 60 and to the frame at 66. To rotate the arm 68 of the bell crank lever by the reciprocation thus imparted to the slide 60, I provide the pin 67 in 45 the slide 60 and projecting outwardly therefrom to engage the arm 68 adjacent its end. As indicated in Fig. 6, the slide 60 is provided with a number of holes, each one of which is adapted to receive the said pin 67 and I am thereby 50 enabled to adjust the relative movement of the carriage 1 and bell crank arm 68. It is thus apparent that sideways reciprocation of the carriage 1 rotates arms 68 and 70 of the bell crank lever and, through the various linkages hereinabove described, thereby elevates and depresses

5 the arms 46 (Fig. 1) which carry the feed finger mechanism.

As stated above, the feed fingers 51 are yielding urged in a clockwise direction (as shown in Fig. 2) about the axis of the bar 50, by means 5 of the spring 52 whereby to ensure insertion of the fingers behind the flap of the foremost envelope during vertical reciprocation of the fingers, and for the purpose of moving the lower edge of the foremost envelope over the extensions 126 I provide that the feed fingers 51 are at times given a slight counter-clockwise rotation about the axis of the bar 50. This counter-clockwise rotation is automatically imparted to the fingers 51 upon downward motion of the bar 50 15 by means of an adjustable cam surface 55 on the right-hand edge of the front wall 30a of the container and adapted to be engaged by the cam roller 54 carried by the lower end of an arm 53 fixed to the extremity of the bar 50, which, it 20 will be remembered, is rotatably mounted in bearings in the extremities of the vertically reciprocable arms 46. The cam surface 55 is so positioned vertically of the front wall 30, relative to the length of the arm 53 that the desired 25 counter-clockwise rotation is imparted to the feed fingers 51 after they have entered the flap and while they are approaching the fold of the flap.

30 As described above, the vertical reciprocation of the feed fingers 51, obtained through a corresponding movement of the side arms 46, is effected each time the carriage 1 of the typewriter is moved to its extreme right-hand position at the completion of a line of typing. The name and address which is typewritten on an envelope customarily occupies three horizontal lines spaced vertically from each other, thus necessitating for each complete name and address three lateral reciprocations of the typewriter carriage. As 35 each envelope being typed remains in the machine during three lateral reciprocations of the carriage, it is desirable to prevent feeding of succeeding envelopes by the feed fingers 51 until the last reciprocation. It will be noted that after the first line of typing, customarily comprising the name of the addressee, each movement of the carriage to the right is accompanied by a feeding movement of the platen roll to provide the proper vertical spacing for the first line of 40 the address. To prevent feeding by the fingers 51 until the last reciprocation of the carriage 1, I provide that for each lateral reciprocation of the carriage during which the spacing lever 4 45 is also actuated, to space the lines vertically, the feed fingers 51 move forwardly into inoperative position so that they do not engage behind the flap of the foremost envelope and no feeding by the fingers 51 takes place.

55 For that purpose the bar 50 to which the feed fingers 51 are secured is provided at its extremity opposite to that to which the cam lever 53 is secured, with a second cam lever 56 having a cam roller 57 bearing on the edge of the cam lever 93. The said cam lever 93 is pivoted at 92 to the frame and is connected, intermediate its ends, to the arm 89 (Fig. 4), the opposite end of which arm is pivoted at 88 to the lever 86 pivoted at 87 to the frame and guided in its rotational movement by the pin 87b projecting from the frame and received in the arcuate slot 87a in the lever 86. A spring 94 secured to the stud shaft 87 bears against the lever 86 to urge the lever 86 to the limit of its counter-clockwise rotation as determined by the pin 87b and slot 87a, as indicated in Fig. 4.

The downwardly depending nose 86a of the lever 86 extends into the path of movement of a bar 85 which (Fig. 3) is wedge-shaped at its end. The plate 80 (Fig. 4) to which the bar 85 is secured is mounted on the side of the frame of the machine for longitudinal reciprocation by means of the studs 82 working in the elongated slots 81. Longitudinal movement of the bar 80 is effected upon movement of the spacing lever 4, which, for that purpose, is provided with a nose 83 (Fig. 3) which co-operates with the projection 82a on the lever 80 to move the bar 80 longitudinally and toward the lever 86 each time the spacing lever 4 is actuated, as will be apparent.

As is customary, the lever 4 is operated manually for the purpose of vertically spacing the typing lines at the beginning of the lateral reciprocation of the carriage 1 which returns the carriage to its starting position. During this return movement of the carriage, the lever 4 is held to the limit of its counter-clockwise rotation (Fig. 3). The result of this combined movement is to hold the slide 80 in its rearward position during the return stroke of the carriage and the beveled nose 85 of the slide 80 thereby reciprocates in a path which includes the nose 86a of the lever 86 to actuate the same.

The mechanism above described which actuates the feed fingers 51 at the proper intervals and which also ensures that they remain inoperative at the proper moments, is effective to remove the foremost envelope from the stack 37 and deposit it in the bite of the feed rollers 12 and 20. The stroke of the feed fingers 51 is designed to deposit the lowermost edge of the envelope between the knurled rollers 12 and 20 which are yieldingly held together and it will be observed from Fig. 3 that the feed fingers 51 are not aligned vertically above the feed rollers 12 and 20 so that the fingers themselves do not enter between the rollers.

The rotational movement of the platen roll 2 and feed rollers 20, 12 and 25 which has in part been described above and which will be amplified hereinafter, is so designed that when the first envelope is in position in front of the platen roll 2 for the typing of the first line, customarily comprising the name of the addressee, the lowermost edge of the next succeeding envelope will just have been received in the bite of the feed rollers 12 and 20. The typing of the first line on the first envelope then proceeds and at the completion of that line of typing the carriage 1 is given a longitudinal movement to the right to return the carriage to its initial typing position and this return movement is accompanied by a spacing rotation of the platen roll 2 to provide the proper vertical spacing for the second line of typing. This return reciprocation of the carriage 1 and spacing rotation of the platen roll 2 is effected simultaneously by a movement to the right (Fig. 3) of the lever 4 in the usual manner. The rotational movement of the platen roll 2 imparts a similar movement to the feed rollers 12 and 20 to advance the second envelope a small amount corresponding to the vertical distance between the horizontal lines of typing. The feed fingers 51 will reciprocate during this return movement of the carriage 1, but will be inoperative due to the action of the cam lever 93 and arm 56 (Fig. 2).

A similar movement will take place at the end of the second line of typing which will advance the second envelope another small amount by rotation of the feed rollers 12 and 20 and so on

for the third line of typing, the second envelope advancing a slight amount each time the platen roll 2 is given a spacing movement. At the completion of the third line, the first envelope is ready to be removed from the typewriter and the second envelope must be fed from its intermediate position to the proper position in front of the platen roll 2 for the typing of the first line. The rotational movement of the platen roll 2 and feed rollers 12, 20, and 25 necessary to eject the first envelope from the machine and simultaneously to position the second envelope in the proper place for the typing of its first line is effected by one stroke of the lever 101 (Fig. 1).

The mechanism associated with the lever 101 which ejects the first envelope and simultaneously feeds the second envelope to typing position upon movement of that lever will now be described.

As indicated by a comparison of Figs. 7 and 8, 20 the lever 101 terminates in a hub 100 rotatably mounted on the stud 27. The hub 100 has secured to its periphery a plate 98 which is surrounded by the enlarged annular sleeve 109 integral with hub 110 also journaled on the stud 27. As indicated in Fig. 9, the plate 98 is cut away at intervals around its periphery, as indicated at 107, to form wedge-shaped slots receiving the cylindrical rollers 108, the diameter of which is slightly less than the widest end of the slot 107. The rollers 108 are spring-pressed away from the wide ends of the slots and toward the narrow ends by compression springs 111 received in orifices drilled in the plate 98, as indicated in the drawings. The rollers 108 are retained in the slots 107 by means of the plate 99 (Fig. 8) covering the open side of the slots 107.

It will be apparent from this construction that the manual counter-clockwise rotation of the lever 101 with its integral plate 98 will be effective to jam the rollers 108 in the slots 107 and against the annular sleeve 109 to effect a corresponding counter-clockwise rotation of the sleeve 109. Return movement of the lever 101 will not, however, effect a corresponding movement of the sleeve 109.

The hub 110 on which the annular sleeve 109 is formed is connected to the gear 28 by clutch mechanism to be described but which clutch mechanism is in engaging position during the said counter-clockwise movement of the lever 101 so that a similar counter-clockwise rotation of the gear 28 is effected, which, through the gear 29 (Fig. 7) and pinion 14 (Fig. 8) effects a clockwise feeding rotation of the platen roll 2 and a similar feeding movement of the feed rollers 12 and 20.

For the purpose of adjusting the throw of the lever 101 and the corresponding extent of feed movement of the platen roll 2 and feed rollers 12 and 20, I provide, for co-operation with the lever 101 an adjustable stop 105 in the form of a bolt extending through the arcuate slot 103 in the guide piece 104, the stop 105 being secured in any desired position in the slot 103 by means of the thumb screw 106. The lever 101 is provided with a finger 102 also received by the slot 103 and adapted to travel therein during the feeding movement of the lever 101, which finger 102 abuts the adjustable stop 105 at the desired limit of the feeding movement. The lever 101 may be manually returned to its Fig. 7 position or preferably suitable springs may be provided for effecting this movement automatically upon release of the lever.

The clutch mechanism above referred to which connects the gear 28 with the hub 110 and associated mechanism operating with the lever 101, is provided for the purpose of enabling the typist 5 to rotate the platen roller manually in a counter-clockwise direction as viewed in Fig. 1 and contrary to the direction of the usual feeding rotation, if such movement is desired, without moving the lever 101.

10 The hub 116 of the gear 28 is provided with clutch teeth 115 adapted to engage the co-operating clutch teeth 114 on the annular hub 112 which is mounted on the outer surface of the sleeve 110 carried by the stud 27. The hub 112 15 is secured to the sleeve 110 for rotation therewith and reciprocation thereon, by a spline or other suitable connection such as the pins 113 projecting inwardly from the inside surface of the hub 112 and working in the elongated slots 20 110a of the sleeve 110. With the hub 110 positioned as indicated in Fig. 3, with the teeth 115 and 114 in engagement with each other, rotation of the sleeve 110 through the mechanism above-described and actuated by the hand lever 25 101, will impart a similar rotation to the gear 28 and thence to the platen roll and the feed rollers 12, 20, and 25. If the clutch hub 112 be now manually moved away from the gear 28 and in the direction of the retaining washer 30 117 so that the clutch teeth 115 and 114 are out of engagement, the platen roll 2 may be manually rotated in either direction without moving the lever 101. Although such movement of the clutch is necessary to provide a free movement 35 of the platen roll 2 in a counter-clockwise direction as viewed in Fig. 1, it is unnecessary to disengage the clutch for the usual clockwise feed of the platen roll, such as by the spacer lever 4, as the roller mechanism illustrated in 40 Fig. 9 permits such movement free of the lever 101, and therefore the clutch need not be disengaged each time the spacer lever 4 is actuated.

With the mechanism constructed as above described its operation is as follows:

45 A stack of envelopes is placed in the magazine supply on the table 35 between the stop 38 and pusher 39, with their flaps at the bottom and facing forwardly. The typewriter carriage is then moved to the right without actuating the spacer 50 lever 4, until the platen roll has come to position for the typing of the first letter of the first word at the left hand side of an envelope. Usually a stop is provided on the typewriter to stop the carriage reciprocation at this point. During 55 this movement the feed fingers 51 have moved downwardly along the surface of the foremost envelope in the pack and because of the spring 52 have passed between the back of the envelope and the seal flap and thus engage the envelope. 60 Just prior to their reaching the fold of the flap in their downward movement the cam roll 54 engages the cam surface 55 and rotates the bar 50 and the fingers 51 to oscillate the fingers and to draw the engaged envelope away from the table 35 to allow passage of this one envelope 65 downwardly. As the carriage comes to rest against its stop at its right-hand position, the feed fingers come to rest in a position to feed the first envelope to the knurled rollers 12 and 20, the pin 67 on the slide 60 at the back of the carriage being properly adjusted for this movement. The envelope is then brought to typing position by two movements of the lever 101 which rotates the ingoing rolls 12 and 20 (and the 70 platen roll 2) simultaneously and with equal pe-

ripheral velocity. Before typing this first envelope the carriage is given an additional movement to the left and back to the right again, to feed the second envelope to a position between the rollers 12 and 20. The first line, usually 5 the name of the addressee, is then typed. During this typing the typewriter carriage moves back to the left and the feed fingers rise again through action of the springs 48.

When the first line of typing is completed the 10 operative moves the envelope to position for typing the second line, usually the street address, by rotation of the platen roll by means of the spacing lever 4 in the usual manner. This rotation at the same time moves the second envelope 15 in the feed rollers 12 and 20 and advances it towards the platen roll. At the same time the operative moves the carriage to the right by pressure on the spacing lever 4 to bring the envelope back to position just under the first letter 20 of the first line. As the carriage is reciprocated by the spacing lever, the feed fingers 51 are again actuated downwardly. This time, however, inasmuch as the carriage was moved to the right simultaneously with actuation of the spacing 25 lever 4 the detent 85 strikes nose 86a and the cam surface 93 (Fig. 4) has been moved into the path of the cam roll 51 and the fingers 51 as they move downwardly have been oscillated 30 away from the flap of the third envelope which is now foremost in the pack in the magazine, so as not to engage that envelope.

After the second line of typing has been completed the operative repeats the rotation of the platen roll and the movement of the carriage 35 to the right by the spacer lever 4 to bring the envelope to position for typing the third line, usually the city address. This further advances the second envelope. For the same reason as in the first spacing lever operation the said 40 fingers, while moved downwardly, are prevented from engaging a flap of an envelope by reason of the rotation of bar 50 by the cam surface 93 and cam lever 56.

Having finished the typing of this envelope the 45 operative pulls the lever 101 forwardly and downwardly until it is stopped by the pin 102 engaging the adjusted stop stud 105, which movement rotates the knurled rollers 12 and 20 and the platen roll 2 sufficiently to bring the second 50 envelope to a position on the platen roll where the name is to be affixed. The first envelope which has already been typed is simultaneously ejected from the platen roll after passing beneath the usual auxiliary rolls 125 and are 55 gripped between the knurled rollers 25 and 12 which feed the envelope upwardly against the guides 95 which turn the envelope over and as it is freed from the rollers it drops address side down directly onto the receiving rack 96.

The operative then returns the carriage to the right to bring the second envelope into its horizontal type-starting position by any means other than the spacing lever, such as moving it by pushing on the platen roll handle. Simultaneously with this movement the feed fingers engage and feed the third envelope down to rollers 12 and 20.

This operation is then repeated to type successive envelopes, the cycle beginning with the 70 completion of typing of the second envelope being one stroke of the lever 101, movement of the carriage to the right, movement of the spacer lever 4 twice. In this manner after slight practice an operative may very rapidly 75

feed the successive envelopes to the typing position and through the typewriter. If for any reason it is necessary to reverse the direction of the platen roll this may be easily done by sliding the clutch 112 out of engagement so that the gear 28 may freely rotate in a clockwise direction without hindrance by the lever 101.

Once the proper adjustment of the pin 67 on the slide 60 is secured and the stop stud 105 0 is placed in a proper position for a predetermined amount of movement of the rollers and platen roll according to the width of the envelope being used, the operation of my feeding device is very rapid, and the operative does not 15 need to handle the envelopes during the entire operation.

I claim:

1. Apparatus for feeding material to be printed in a device having a platen roll on a reciprocating carriage, comprising feed mechanism actuated by reciprocation of said carriage and rotary elements adapted to receive therebetween material from said mechanism and to intermittently further feed said material to said platen 25 roll, said elements operating synchronously with rotation of said platen roll and dissociated from operation of said feed mechanism.

2. In envelope feeding apparatus for typewriters having a platen roll on a reciprocating carriage, a magazine for envelopes, means to feed an envelope from said magazine, said means being actuated by reciprocation of said carriage, rotary elements adapted to receive therebetween said envelope from said feeding means and to 35 further feed said envelope to said platen roll, said elements reciprocating with said carriage, and rotatable synchronously with rotation of said platen roll.

3. In combination with a typewriter having a rotatable platen roll on a reciprocating carriage and having spacing means for rotating said platen roll a predetermined distance in feed direction, rotary elements adapted to feed material to be printed to said platen roll, said elements being geared to said platen roll, and selective mechanism operating independently of said spacing means to rotate said elements and said platen roll a predetermined distance greater than that caused by said spacing means, to feed material from a position between said rotary elements to a predetermined typing position about said 50 said platen roll.

4. In combination with a typewriter having a rotatable platen roll on a reciprocating carriage, auxiliary rotary elements adapted to feed material to said platen roll, said elements operating synchronously with rotation of said platen roll, selective mechanism to rotate said elements and platen roll a predetermined distance in feed direction, means to permit rotation of said platen roll and said elements in feed direction independent of said selective mechanism, and a clutch operative to allow rotation of said platen roll and elements in either direction independent of said selective mechanism.

5. Apparatus for feeding material to a typewriter having a rotatable platen roll on a reciprocating carriage, comprising a magazine, feed fingers actuated by reciprocation of said carriage and adapted to feed material from said magazine, auxiliary rotary elements on said carriage adapted to receive said material from said fingers, a plurality of ratchet levers and connecting mechanism to independently rotate said platen roll and said elements simultaneously in

feed direction, one of said levers operative to rotate said platen roll and said elements a predetermined distance, another lever operative to rotate said platen roll and said elements a different predetermined distance, and means operative to permit rotation of said platen roll and elements in either direction without movement of said levers.

6. Apparatus for actuating material in combination with a typewriter having a rotating platen roll on a reciprocating carriage, comprising a magazine for material to be fed, reciprocating feed mechanism actuated by reciprocation of said carriage and adapted to normally feed material from said magazine, rotary elements adapted to receive said material from said feed mechanism, said elements being rotatable synchronously with said platen roll and adapted to feed said material to said platen roll, means to rotate said platen roll in feed direction, including a plurality of levers, one of said levers being operative in one stroke to move said material a predetermined distance to typing position, said other lever simultaneously with rotation of said platen roll actuating mechanism operative to prevent said reciprocating feed mechanism from feeding material in actuation of the carriage by said other lever.

7. In a feed attachment for typewriters, a magazine for material to be printed, reciprocating fingers normally adapted to feed said material from said magazine and selective means operative to prevent said fingers from feeding material in reciprocation thereof.

8. In combination with a typewriter having a reciprocating carriage, a stationary supply magazine, reciprocating fingers adapted to feed material to be typed from said magazine, said fingers being actuated by reciprocation of said carriage, and selective means to reciprocate said carriage while preventing said fingers from feeding said material.

9. Apparatus for feeding material to a typewriter having a reciprocating carriage, comprising a magazine adapted to contain said material, reciprocating feed mechanism adapted to feed material from said magazine, a reciprocating slide, having an adjustable pin, a lever mechanically connected with said feed mechanism and disposed in the path of said reciprocating pin, a fixed element on said carriage, said slide being in the path of said element, whereby said feed mechanism is reciprocated by actuation of said carriage.

10. In apparatus for feeding material to be printed from a supply to printing position on a platen roll, feed fingers adapted to engage and feed material to be printed, means for supporting said feed fingers adjacent the supply of material, means to reciprocate said supporting means, means for yieldingly urging said fingers into a feeding path contiguous to the material, and selective means to move said fingers into a non-feeding path relatively remote from said material in actuation of said supporting means.

11. In apparatus for feeding material to a platen roll mounted on a reciprocating carriage, a supply magazine, feed fingers adapted to engage and feed material to be printed, means for supporting said feed fingers adjacent said supply, means to reciprocate said fingers, said means being actuated by lateral reciprocation of said carriage, means for yieldingly urging said fingers into a feeding path contiguous to said material, and selective means to move said fingers in-

to a non-feeding path relatively remote from said material in reciprocation of said fingers.

12. In combination with a typewriter having a reciprocating carriage, including a platen roll and mechanism to rotate said platen roll, a supply magazine, reciprocating oscillating fingers adapted to feed material to be typed from said supply, said fingers being actuated by reciprocation of said carriage, and selective means to oscillate said fingers in reciprocation of said carriage to prevent said fingers from feeding said material.

13. In an envelope feeding attachment for a typewriter, a magazine adapted to hold material to be fed, a reciprocating oscillating bar having feed fingers adapted to engage said material, a cam lever mounted on said bar, and a cam surface adapted to be moved into the path of said cam lever and to engage said cam lever as said bar reciprocates to oscillate said bar and said 20 fingers to prevent said fingers from engaging said material.

14. Apparatus for feeding material to a typewriter having a rotatable platen roll on a reciprocating carriage, comprising a magazine, feed mechanism actuated by reciprocation of said carriage and adapted to feed material from said magazine, a plurality of ratchet levers and connecting mechanism to independently rotate said 25 platen roll in feed direction, one of said levers operating to rotate said platen roll a predetermined distance, another lever operating to rotate said 30

platen roll a different predetermined distance, and means operating to permit rotation of said platen roll in either direction without movement of said levers.

15. Apparatus for actuating material in combination with a typewriter having a rotating platen roll on a reciprocating carriage, comprising a magazine for material to be fed, feed mechanism actuated by reciprocation of said carriage and adapted to normally feed material from said magazine, means to rotate said platen roll in feed direction, including a plurality of levers, one of said levers being operative in one stroke to move said material a predetermined distance to typing position, said other lever simultaneously with rotation of said platen roll actuating mechanism operating to prevent said feed mechanism from feeding material in actuation of the carriage by said other lever.

16. In combination with a typewriter having a shaft carrying a rotatable platen roll, a pinion mounted on said platen roll shaft, geared shafts mounted on said typewriter and carrying auxiliary rotary elements adapted to feed material to said platen roll, a driven element mounted on one of said shafts, a driving element engaging said driven element and adjustably pivoted thereabout to also engage said pinion, and a lever to rotate said driving element.
